CLAIM

The ornamental design for a cover for a condenser unit as shown and described.

DESCRIPTION

FIG. 1 is a top and front perspective view of a cover for a condenser unit in an environmental structure;

FIG. 2 is a front elevational view thereof;

FIG. 3 is a left side elevational view thereof;

FIG. 4 is a rear elevational view thereof;

FIG. 5 is a right side elevational view thereof;

FIG. 6 is a top plan view thereof;

FIG. 7 is a bottom plan view thereof; and,

FIG. 8 is a bottom and front perspective view thereof.

The broken lines in the drawings show portion of the cover for a condenser unit and the environmental structure of the cover for a condenser unit and form no part of the claimed design.

1 Claim, 5 Drawing Sheets
